UNITED STATES PATENT OFFICE.

IVER NIELSON, OF KINDRED, DAKOTA TERRITORY.

DESIGN FOR A PATTERN FOR SHOE-UPPERS.

SPECIFICATION forming part of Design No. 17,281, dated April 26, 1887.

Application filed December 4, 1885. Serial No. 184,757. Term of patent 14 years.

To all whom it may concern:

Be it known that I, IVER NIELSON, a subject, as yet, of the King of Norway, Europe, residing at Kindred, in the county of Cass 5 and Territory of Dakota, have invented and produced a new and original Design for a Pattern for Shoe-Uppers, of which the following is a specification, reference being had to the accompanying photograph, forming part 10 thereof.

The figure represents a front elevation of my design for a pattern or blank for a shoe-upper.

The leading features of the design are shown in the top lines, which are scalloped, as shown 15 at 2 2, and are continuous with the sides, carrying said sides down with ogee curves 4 4, and continuing the bottom or base line of the pattern in an acutely curved or projecting belly

or central portion, as shown at 1. The design also has the central opening or separation, 3^a, 20 the left-hand line of same being rounded off at the point where it terminates in the top line.

What I claim and desire to protect is—

A design for a pattern for shoe-uppers, having the flaring central opening between the 25 lines 3^a, said lines being continuous with the top line and the left-hand one thereof being rounded off at its juncture therewith, the scalloped top line continuing in the ogee-curved sides 4 4 and terminating in an acutely-curved 30 bottom or base, substantially as shown and described.

IVER NIELSON.
